[57] CLAIM

The ornamental design for a template, as shown.

DESCRIPTION

FIG. 1 is a top plan view of a template showing my new design, the bottom plan view being a mirror image; FIG. 2 is a right side elevational view, the left side elevational view being identical; and

FIG. 3 is a top plan view of another embodiment of FIGS. 1 and 2 thereof, the bottom plan view being a mirror image.

FIG. 1

FIG. 2

FIG. 3
